UNITED STATES PATENT OFFICE.

LEWIS C. BAYLES, OF EASTON, PENNSYLVANIA, ASSIGNOR TO INGERSOLL-RAND COMPANY, OF NEW YORK, N. Y., A CORPORATION OF NEW JERSEY.

PERCUSSIVE TOOL.

1,081,653.

Specification of Letters Patent.

Patented Dec. 16, 1913.

Application filed February 3, 1912. Serial No. 675,289.

To all whom it may concern:

Be it known that I, LEWIS C. BAYLES, a citizen of the United States, and resident of Easton, in the county of Northampton and 5 State of Pennsylvania, have invented a new and useful Improvement in Percussive Tools, of which the following is a specification.

The object of my invention is to provide 10 a percussive tool having a novel form of rotation device, the device being operated independently of the work piston.

In the accompanying drawings, Figure 1 represents in longitudinal central section a 15 percussive tool of the piston hammer type with my improved rotation device applied thereto. Fig. 2 is a transverse section taken in the plane of the line A—A of Fig. 1. Fig. 3 is a transverse section taken in the 20 plane of the line B—B of Fig. 1. Fig. 4 is a front end view of the rotation controlling piston. Fig. 5 is a side view of the same, Fig. 6 is a side view of the rotation controlling ring, Fig. 7 is a detail longitudinal central section through the tool in a plane at right angles to Fig. 1, and Fig. 8 is a diagrammatic view showing more clearly the passages connecting the several parts.

30 The work piston is denoted by 1 and the chamber in which it reciprocates by 2. The anvil block is denoted by 3 and the shank of the drill steel by 4. The cylinder in which the work piston 1 and anvil block are located is denoted by 5 and the usual handle 6 may be attached in any suitable manner at the rear end of said cylinder, a back head 7 being interposed between the cylinder and handle. The rotary chuck is denoted by 8, 35 and it is provided with an enlarged bore 9, in which the front end of the cylinder 5 extends to form a bearing for said chuck. A hollow sleeve 10 surrounds the cylinder 5 and is spaced therefrom to form a rotation 40 controlling piston chamber 11. The rear end of this sleeve 10 engages a circumferential flange 12 on the cylinder 5. The front end of this sleeve 10 is engaged by a ring 13 which surrounds the chuck 8. A rotation 45 controlling piston 14 is fitted to reciprocate in the chamber 11. A rotation controlling ring 15 is rotatably mounted in the bore of the hollow sleeve 10, and it has a pawl and ratchet engagement with the chuck 50

8. In the present instance, the chuck 8 is provided with one or more spring-pressed pawls 55 16 and the bore of the rotation controlling ring 15 is provided with an annular series of ratchet teeth arranged to be engaged by the said pawl or pawls 16.

The annular rotation controlling piston 14 has an interlocked sliding engagement 60 with the cylinder 5, and with the rotation controlling ring 15. In the present instance, the rotation controlling piston has a straight 65 tongue and groove connection 17, 18, with the cylinder 5 and a spiral tongue and groove connection 19, 20, with the rotation controlling ring 15.

A motive fluid controlling valve 21 is 70 mounted to reciprocate in the valve chest 22, shown herein as formed integral with the cylinder 5, which valve is arranged to separately control the movements of the work piston 1 and rotation controlling piston 14, 75 as follows: Motive fluid passages 23, 24, lead from the front and back ends of the work piston chamber 2 to the face of the valve 21, and motive fluid passages 25, 26, lead from the front and back ends of the rotation controlling piston chamber 11 also to the face 80 of the controlling valve 21. The main motive fluid supply port is denoted by 27, and main exhaust ports by 28, 29. The bridge ports 30, 31, in the valve 21, alternately open 85 the front and back ends of the work piston chamber and the rotation controlling piston chamber to the motive fluid supply port 27 and exhaust ports 28, 29.

From the above description it will be seen 90 that a very compact rotation device is provided for the tool, said rotation device being operated from the controlling valve independently of the work piston.

While I have shown and described my invention in connection with a percussive tool of the piston hammer type, I do not wish to be limited to such a construction but contemplate its use in connection with percussive tools of any type.

100 What I claim is:—

1. In a percussive tool, a work piston, a chuck, an oscillating rotation controlling ring having a driving connection with the chuck, a reciprocating annular rotation controlling piston movable longitudinally of the tool and having a driving connection 105 with said ring and means arranged to con-

- trol the admission of the motive fluid to the two pistons for operating them.
2. In a percussive tool, a work piston, a chuck, a reciprocating annular rotation controlling piston having a driving connection with the chuck and movable longitudinally of the tool and a valve arranged to control the admission of the motive fluid to the two pistons for operating them.
- 10 3. In a percussive tool, a work piston, a chuck, an oscillating rotation controlling ring having a driving connection with the chuck, a reciprocating annular rotation controlling piston movable longitudinally of the tool and having a driving connection with the ring, and a valve arranged to control the admission of the motive fluid to the two pistons for operating them.
- 20 4. In a percussive tool, a cylinder, a work piston, a chuck, an oscillating rotation controlling ring having a driving connection with the chuck, a reciprocating annular rotation controlling piston movable longitudinally of the tool and having a sliding 25 interlocked connection with both said cylinder and said rotation ring and means for operating said pistons.
- 30 5. In a percussive tool, a cylinder, a work piston, a chuck, an oscillating rotation controlling ring having a driving connection with the chuck, a reciprocating annular rotation controlling piston movable longitudinally of the tool and having a spiral tongue and groove sliding connection with the rotation 35 controlling ring and a straight tongue and groove sliding connection with the cylinder and means for operating the pistons.
- 40 6. In a percussive tool, a cylinder, a work piston, a chuck, an oscillating rotation controlling ring having a driving connection with the chuck, a reciprocating annular rotation controlling piston movable longitudinally of the tool and having an interior 45 straight tongue and groove sliding connection with the cylinder and an exterior spiral tongue and groove sliding connection with
- the rotation controlling ring, and means for operating said pistons.
7. In a percussive tool, a cylinder, a work piston, a chuck, an annular rotation controlling piston fitted to reciprocate longitudinally of the tool and means connecting the rotation controlling piston with the chuck for rotating said chuck from said annular piston.
- 50 8. In a percussive tool, a cylinder, a work piston, a chuck, an annular rotation controlling piston fitted to reciprocate longitudinally of the tool, means connecting the rotation controlling piston with the chuck for rotating said chuck from said annular piston, and means for operating said pistons.
- 55 9. In a percussive tool, a cylinder, a work piston, a chuck fitted to rotate, an annular rotation controlling piston fitted to reciprocate longitudinally of the tool and substantially concentric with said work piston and means connecting the rotation controlling piston with the chuck for converting the reciprocative movements of the rotation controlling piston into rotative movement of said chuck.
- 60 10. In a percussive tool, a cylinder, a work piston, a chuck fitted to rotate, an annular rotation controlling piston fitted to reciprocate longitudinally of the tool and substantially concentric with said work piston, means connecting the rotation controlling piston with the chuck for converting the reciprocative movements of the rotation controlling piston into rotative movement of 65 said chuck, and means for operating the pistons.
- 70 75 80
- In testimony that I claim the foregoing as my invention I have signed my name in presence of two witnesses, this first day of February, 1912.
- LEWIS C. BAYLES.
